US00D924870S

(12) **United States Design Patent** (10) **Patent No.:** **US D924,870 S**
Zhang (45) **Date of Patent:** **** Jul. 13, 2021**

(54) **SMART BRACELET**

(71) Applicant: **SHENZHEN AUKEY SMART INFORMATION TECHNOLOGY CO., LTD.**, Shenzhen (CN)

(72) Inventor: **Minmin Zhang**, Shenzhen (CN)

(73) Assignee: **SHENZHEN AUKEY SMART INFORMATION TECHNOLOGY CO., LTD.**, Shenzhen (CN)

(**) Term: **15 Years**

(21) Appl. No.: **29/683,390**

(22) Filed: **Mar. 13, 2019**

(51) LOC (13) Cl. **14-02**

(52) U.S. Cl.

USPC **D14/344**

(57) **CLAIM**

The ornamental design for a smart bracelet, as shown and described.

DESCRIPTION

FIG. 1 is a perspective view of a smart bracelet showing my design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of another state of the smart bracelet; and,

FIG. 9 is a perspective view of another state of the smart bracelet.

The broken lines shown in the drawings depict portions of the smart bracelet in which the design is embodied that form no part of the claimed design.

1 Claim, 9 Drawing Sheets
